US00D896455S

(12) **United States Design Patent** (10) **Patent No.:** **US D896,455 S**
(45) **Date of Patent:** **** Sep. 15, 2020**

(54) **WASHING MACHINE**

(71) **Applicant:** **LG ELECTRONICS INC.**, Seoul
(KR)

(72) **Inventors:** **Yanghwan No**, Seoul (KR); **Minkyu Oh**, Seoul (KR); **Seongwoo An**, Seoul (KR); **Yongnam Kim**, Seoul (KR)

(73) **Assignee:** **LG ELECTRONICS INC.**, Seoul
(KR)

(**) **Term:** **15 Years**

(21) **Appl. No.:** **35/507,441**

(22) **Filed:** **Nov. 22, 2018**

(80) **Hague Agreement Data**

Int. Filing Date: **Nov. 22, 2018**
Int. Reg. No.: **DM/202711**
Int. Reg. Date: **Nov. 22, 2018**
Int. Reg. Pub. Date: **Sep. 13, 2019**

(57)

CLAIM

The ornamental design for washing machine, as shown and described.

DESCRIPTION

1. Washing machine

1.1 : Perspective

1.2 : Front

1.3 : Back

1.4 : Left

1.5 : Right

1.6 : Top

1.7 : Bottom

The broken lines indicate portions of the article that form no part of the claimed design.

1 Claim, 7 Drawing Sheets
